RAZOR AND BLADE DISPENSER THEREFOR

Gordon M. Peitz, Montclair, N. J., and Robert H. Ensign, Bronxville, N. Y., assignors to American Safety Razor Corporation, Brooklyn, N. Y., a corporation of Virginia

Application April 21, 1953, Serial No. 350,058

34 Claims. (Cl. 30—40)

This invention relates to razors and to blade stacking containers devised therefor.

Other objects of the invention are the following: to provide a new and improved container and blades stacked therein, each having an underlying channel to facilitate their removal in succession; to provide a container whereby removal of the blades directly into a razor is simplified; to provide an improved razor blade container having a loading zone adapted to receive a razor and automatically to couple a fresh blade in said razor; to provide an improved container having an extracting zone for automatically removing a used blade from a razor; to provide an improved container which is inexpensive and simple to manufacture; and to provide an improved container which is compact, rugged and durable and has an attractive appearance.

Further objects of the invention are to provide an improved razor particularly devised for cooperation with a razor blade; to provide an improved razor particularly devised for cooperation with said container to permit discharge of blades therein; to provide a safety razor which automatically will withdraw a fresh razor blade from said container when inserted into and withdrawn from a loading zone thereof, and which automatically will discharge a used blade into the container when inserted into and withdrawn from an extracting zone thereof; to provide a razor which will grip a razor blade tightly during and after withdrawal thereof from the loading zone of the container; to provide a razor which automatically will center the razor blade therein and will maintain the edges of the blade parallel to the guard of the razor; to provide a razor which is simply and inexpensively manufactured and is convenient and safe to use; and to provide a razor which is rugged and durable.

A further object of this invention is to provide an arrangement whereby manual handling of either the new or used blade is eliminated.

The accompanying drawings illustrate the preferred form of the invention. In the drawings:

Fig. 1 is a sectional side view of a container constructed in accordance with the present invention, the loading zone being lowermost;

Fig. 2 is a partially broken away end view of the container shown in Fig. 1, the view being taken to show the loading zone;

Fig. 3 is a top view of the container;

Fig. 4 is an enlarged fragmentary sectional view taken substantially along the line IV—IV of Fig. 2, and showing the razor fully inserted during the loading operation;

Fig. 5 is a sectional view taken substantially along the line V—V, of Fig. 4;

Fig. 6 is an enlarged sectional view taken substantially along the line VI—VI of Fig. 2 and showing the razor fully inserted during an extraction operation;

Fig. 7 is a sectional view taken substantially along the line VII—VII of Fig. 6;

Fig. 8 is a sectional view taken substantially along the line VIII—VIII of Fig. 1;

Fig. 23 is a side elevation of the frame shown in Fig. 22;

Fig. 24 is a side elevation of the bridge member of the razor;

Fig. 25 is a top plan view of the bridge member shown in Fig. 24; and

Fig. 26 is a perspective view showing a modification of the extracting guide.

Referring now in detail to the drawings, the reference numeral 20 denotes a container, the reference numeral 22 a safety razor, and the reference numeral 24 a razor blade embodying the instant invention.

Pursuant to the instant invention, the novel blade is composite in nature in that it has associated therewith structural elements which function to attain the objects pointed out above. In the embodiment shown in the drawings, which is the preferred form of the invention, this composite blade is illustrated as being formed from the blade proper X and the channel forming member Y.

The blade proper X comprises the more or less conventional double edge strip 54. It will be understood that the invention may be used with any other type of blade, if desired, and that the specification should be read with this thought in mind. The strip 54 is provided with conventional locating means, such as recesses 56 in the drawings. These recesses 56 are of such depth, and so spaced from each other at a given end, that they slidably receive the vertical guide ribs 46 of the container, the relation being such that a minimum of lateral shifting of the blades is permitted.

The second element of the composite blade is the channel forming member Y which adapts the blade proper for the attainment of the objects of the invention. This member Y comprises downwardly projecting elements which are shown in the preferred embodiment of the invention illustrated in the drawings as flanges 58. The flanges 58 are shown in parallel relation to each other and spaced from the slot 64 on opposite sides of the center line of the strip 54. In the embodiment shown in the drawings, these flanges 58 have been shown as uninterrupted, although this is not essential. A cross-piece is provided on the blade to rigidify the blade in a transverse plane. This cross-piece is shown in the drawings as the element 60 which underlies the slot 64 to reinforce the blade

which has been weakened by the slot 64 and extends across

the center line of the blade and for the length of the two flanges 58.

The flanges 58 and the element 60 are shown integral to form generally a U-shaped channel 57, although this is not essential. The flange 58 rigidifies the blade longitudinally. This rigidification enables the strip 54 to be made from very thin gauge material and still maintain substantially the same rigidity of a blade made of conventional blade material. The channel member Y also serves to provide an improved method of stacking the blades in a container and an improved method of locating the blade in a razor, as will be hereinafter pointed out.

The blade proper X and the channel member Y have been shown as separate pieces which are secured together, although this is not necessary. The channel member Y may be secured to the blade proper X in any conventional or desired manner. In the illustrated embodiment this securing is effected as follows: The channel member Y is provided with two upstanding tabs 62 and the strip 54 is provided with slots to receive the tabs, such as the slot 64 shown in the drawings. The tabs 62 are inserted into the slot 64 and folded over as shown in Fig. 13 to secure the channel member Y to the strip 54.

The container comprises a casing having side walls 26 and end walls 28, the casing thus resembling a box. The top wall 21 of the container has a slot 23 opening into the extracting zone and terminating short of the right end wall 28, and the bottom wall 25 of the container has a slot 27 opening into the loading zone and terminating short of the left end wall 28. For ease in construction the container may be made of two identical sections A and B which are reversed and joined to each other along the line C in any conventional manner, or in a manner which will be pointed out hereafter. This enables the two pieces A and B to be made from the same mold. For a reason which later will be apparent, the end wall at the left (as seen in Fig. 1), terminates short of the top and the end wall at the right terminates short of the bottom.

The top of the casing is constructed to function as the extracting zone 30 and the bottom as the loading zone 32. Fresh blades are stacked in the casing above the loading zone and beneath a spring 34 which divides the inside of the casing into a chamber 36 for fresh blades and a chamber 38 for used blades.

The top edge 40 of the left end wall at the extracting zone is shaped to negatively fit the transverse contour of the top surface of the razor cap 206. The bottom edge 44 of the right end wall at the loading zone is similarly shaped. The grooves 45 are provided in side walls of each zone to accommodate the guides 65 and 74 which receive the safety line of the razor as described hereinafter.

The inner surface of each end wall is provided with vertical guide ribs 46 projecting into the casing. The guide ribs of the left end wall are V-shaped on the top as at 47 and those of the right panel are V-shaped at the bottom as at 49.

The upper surface of the right end wall includes a central vertical guide rib 50 between the guide ribs 46 and extends beyond the ends of the guide ribs 46. This rib 50 is tapered at 51 for a purpose which will be hereinafter pointed out. A similar arrangement may be provided with respect to the rib 48 on left end wall since the sections A and B are made from the same mold.

In the present preferred design, the two inverted identical moldings A and B are held together by the action of the projections 71 and 80 of the guides 65 and 74 in co-operation with the recesses 71a and 81.

At the loading zone of the container the loading guide 65 is provided. Said loading guide 65 is comprised of a flat bottom wall 66 having a central longitudinal slot 67 therein terminating short of the right end in Fig. 12 of the loading guide 65 to accommodate the handle 100 of the razor 22. A short central slot 68 is provided at the end of the bottom 66 to accommodate the rib 48 of the casing.

Side walls 69 are provided throughout the length of the loading guide and are contoured, as at 70, complementary to the grooves 45 of the side walls 26 to fit therein. Outwardly biased resilient projections 71 are struck out of the side wall 69 and snap into the recess 71a in the side walls 26 to retain the loading guide 65 in the loading zone 32 and to hold sections A and B together, as pointed out above. Each side wall 69 is provided with a reach 72 and a rib 73 to form an inverted V, the peaks of these V-shaped reach and rib elements 72-73 are spaced apart a distance less than the distance between the sharpened edges of the fresh blade so that the reaches will not dull the edges.

These reaches 72 are disposed below the lower ends 15 of the guide ribs 46 a distance less than the height of the flanges 58 of the blade 24, so that when the strip 54 of the lowermost blade 24 contacts the V-shaped reach and rib element 72-73, the strip 54 of the next to the lowest blade 24' will be under the control of the guide ribs 46 20 because of the separations between the lowermost blade 24 and the next to the lowest blade 24' caused by the flanges 58' of the next to the lowest blade 24' resting on the strip 54 of the lowermost blade 24. The ribs 73 are spaced from each other a distance slightly greater than 25 the distance between the flanges 58 of the fresh blades 24. The lowermost blade 24 is controlled vertically by the coaction of the spring 34 (acting through other blades or directly as the case may be) and the reaches 72; lateral control is obtained by the co-action of the rib 30 73 and the flanges 58; and longitudinal control at the left is exercised by the rib 48, however it can be moved to the right of Fig. 1 and out of mouth 32. The ribs 73 are downwardly inclined to guide flanges 58 into the space 35 between them when a new blade approaches the reaches 72.

At its extracting zone the container is equipped with the extracting guide 74 having a top wall 75. The top wall 75 is provided with a central longitudinal slot 76 at one end to accommodate the razor and a short slot 77 at its other end to accommodate the rib 50. Side walls 78 are contoured, as at 79, complementary to grooves 45 in the side walls 26 of the casing to fit therein. Outwardly biased resilient projections 80 are struck out of the side wall 78 and snap into the recess 81 of the side walls to hold the two sections A and B of the container together 45 and to retain the extracting guide 74 in the extracting zone 30.

Reaches 82 project inwardly from the side walls 78 for about one-half the length of the extracting guide and 50 are spaced from each other a distance slightly greater than the distance between the two flanges 58 of the blade 24. The reaches 82 are disposed above the ends of the ribs 46, a distance sufficient to permit the razor cap 42 to enter. The right ends of reaches 82 serve as a fulcrum about which the strip 54 of blade 24 pivots when moving 55 from a horizontal to an inclined position after the razor has been removed and rotating back again to the horizontal when the next blade is extracted.

Depending from the reaches 82 are two projections 84 60 pressed out of the reaches 82 and spaced from each other a distance substantially equal to the width of the strip 54 of blade 24 to guide used blades 24 laterally.

Notches 85 are cut out of the reaches 82 at a point 65 spaced from the front thereof. The front edge 86 of the notches 85 are twisted downwardly to provide a limit stop for the used blade. An alternative of this limit stop is shown in Fig. 26 where the front edge 86a of the notch 85a is cut out of the wall and bent down and a detent finger 86b extends upwardly beyond the bottom of the reach 82.

The spring 34 which separates the fresh from the used blades is adapted to hold the fresh blades substantially perpendicular to the end and side walls but to cant the right ends of the used blades upwardly with respect to 75 the left ends thereof. To accomplish this the spring com-

prises a central portion 90 (Figs. 1 and 8) including a left stub 91 adapted to slide between the guide ribs 46 of the left end wall. The central portion is also provided with an upwardly extending tongue 92. The central portion 90 has integral therewith on each side thereof side lugs 94 having right toes 98 disposed below the tongue 92. The right toes lie in substantially the same horizontal plane.

Used blades abut the top of the central portion 90 and of the stud 93 of the tongue 92 (see Fig. 1) and are, therefore, canted to the left. The purpose of the canting is to facilitate entry of used blades after insertion of the first used blade since subsequently inserted used blades must pass over the last extracted (inserted) one. Also, the right toes 98 have their ends upwardly concave to facilitate the entry and exit of the razor in the container.

The spring is of such strength that it will prevent the stock of blades from being loose in the dispenser but will permit some upward and downward movement thereof during loading of the razor and extraction therefrom. The spring also should be strong enough so that when at least one and perhaps four or five blades are missing, the remaining blades both used and fresh, if present, will be securely held in the container.

The novel safety razor preferably used with the blade is shown in Figs. 17 to 25. It will be understood that this razor may be of one piece if desired and the choice is only a matter of ease in assembly. The razor comprises a head 202 and a handle 100. The head 202 comprises a rectangular frame 204 having spaced safety bars 208 and the clamping cap 206 integral therewith at rear piece 209. The rear piece 209 is spaced from and is at the same lowered level as the front piece 210 of the frame 204. The slot 212 in the frame 204 and the slot 214 in the cap 206 is provided to accommodate the rib 48 or the rib 50. Two notches 216 are cut out of the inner edge of the front piece 210 and two projections 218 depend therefrom for reasons hereinafter mentioned.

The cap 206 is integral with the frame 204 at 209 and is provided with a central longitudinal rib 220. The rib 220 tapers into the side portions 222 and its front and rear ends are curved as at 224.

The centering bar 200 is a narrow upwardly convex piece 225 underlying rib 220 and having widened base reinforcement 227. It is of such a width as to snugly receive flange 58 of blade 24. The depressed area 226 is provided with an opening 110 for attachment of the handle 100 to the razor 22. It will be understood that the handle 100 may be attached to the razor 22 in any conventional manner, however, in the embodiment shown, the preferred method of attaching the handle 100 to the razor 22 being as follows: the top portion 102 of handle 100 is inserted into the opening 110 and this top is swaged over the depressed region 226 at assembly.

Horizontal flange 228 at its front end extends beyond the sides of the piece 225 and is adapted to underly the slots 216 of the front piece 210 of the frame 204. Outwardly curved projections 229 extending downwardly from rear horizontal flange 230 are adapted to form a clamp for the rear piece 209. Portion 232 extends upwardly from the flange 230 to provide a stop for movement of the blade in the razor.

The head of this razor is assembled as follows: The cap 205 is folded over the frame 204. Handle 100 is attached to the centering bar 200 as described above. The centering bar 200 is then assembled on the frame 204 by first placing the flange 230 over the rear piece 209 of the frame while the projections 229 are pressed on the underside of the rear piece 209. The flange 228 is placed on the underside of the front piece 210 and the projections 218 are pressed under the flange 210 to hold the centering bar tightly in the frame 204.

The cap is biased toward the centering bar so that its undersurface at the front ordinarily is closed to the center bar than at the rear, although not necessarily as close

5

as the middle of said undersurface is to the middle of the centering bar.

The cap is disposed at such a distance from the upper surface of the centering bar for a blade of a given thickness that when the blade is inserted in the razor between the cap and centering bar the cap will be sprung upwardly whereby the cap and bar will clamp the blade between them and hold it tightly in place due to the inherent resilience of the structure. Moreover, the position of the cap preferably is such that the thickness of the blade used will, when the blade is inserted, cause the undersurface of the front end of the cap to be the same distance from the upper surface of the centering bar as the undersurface of the rear end of the cap is from said upper surface, whereby the cap will be parallel to the safety bars after the blade is inserted. For razors to be used with blades of appreciably different thicknesses the relationship between the cap and the centering bar in the empty condition of the razor will have to be altered; with thinner blades the rear end of the cap will have to be closer to the centering bar than with the thicker blades.

The operation of the razor, container and razor blade may best be understood from Figs. 4-7. To load the razor it is inserted into the mouth of the loading zone of the dispenser with the safety bars 208 sliding in the contour 70 of loading guide 65. Said contours 70 are located a distance below the lowermost blade such that the undersurface of the cap of the razor is above the upper surface of said lowermost blade, and the top of the entering end of the centering bar 200 is below the lower surface of said blade. The razor is slid all the way into the mouth, i. e. to the left as viewed in Fig. 4, and the centering bar 200 thereof slides between the flanges 58 of the lowermost razor blade. The left centering rib 48 fits into the recesses 212, 214 at the front of the cap and base of the razor and serves as a stop for the left end of the blade 54. The blade 54 then is stopped by the stud 232 by contact of this stud 232 with the right end of the blade 54. Thus the rib 48 stops the razors through blade 54. With the razor so received in the dispenser the lowermost blade will be inserted fully into the razor. The razor then is moved to the right, withdrawing the blade from the mouth of the loading zone, this being made possible because the clamping friction exerted on the blade by the cap 206 and the centering bar 200.

On removal of the lowermost blade the next lowermost blade is shifted by the spring into lowermost position whereby it is not restrained by the guide ribs 46 of the right end wall and, therefore, is in a position to be loaded into the razor. The contours of the lower surface of the right end wall 28 are shaped to match the contours of the razor cap as aforesaid so that the razor can be smoothly inserted thereunder.

When it is desired to extract a new blade for blade replacement, the razor with the used blade is entered into the extracting zone at one end of the dispenser, and is guided in such movement by the safety bars 208 entered into recessed contours 79 of the guide 74 (see Figs. 6 and 7).

In this entry of the razor into the extracting zone, the blades engage and angle upwardly slightly the depressed portion 86 until the razor is fully entered at which time the blade will have cleared the depressed portion 86 which is then free to angle downwardly to its normal position to engage its front edge in back of the adjacent edge of the blade. As a result when the razor is moved outwardly the blade will be held against movement therewith by the depressed portion 86 and will drop by gravity onto the stack.

The same result is achieved with the modified form of the extracting zone shown in Fig. 26. The purpose of the depressed portion 86 in both embodiments of the invention is to make certain that the ends of the blade will not slip above the depressed portions and slide out above the reaches 82 with the razor. Generally the

70

75

position of contours 79 is such that the bars 208 when in the grooves 45, keep the razor in such a position that the depressed portion 86 abuts the end of the razor blade 54 as the razor is taken out of the container.

When subsequent blades are to be extracted from the container, the razor is not blocked by previously inserted blades from entering the mouth of the extracting zone, because the previously inserted used blades are canted whereby the left end thereof lies below the guide ribs of the left end panel. The stub 93 of the spring engage the container cover when no used blade has yet been extracted, and in this position the toe 91 are below the level at which the grooves 45 dispose the cap, so the latter can depress the spring.

To insure proper location of the blade in the razor, dimples 120 may be provided at the left end of loading guide 65. These dimples 120 are forced up from the surface 66 to such a height as to interfere slightly with the projections 229 of the razor as the razor is inserted. These dimples 120 are so located on surface 66 as to be just to the right of projections 229 when the razor has reached the limit of its movement to the left. As the razor is inserted, the projections 229 press dimples 120 down while passing over them, after which they spring up again. This snap action informs the user both by sound and feel that the razor has been fully inserted and the blade properly seated in the razor.

It will be understood that this invention is not limited to the details of construction described above and shown in the drawings, except as appears hereafter in the claims.

We claim:

1. A razor blade package comprising a blade-containing chamber having a discharge mouth and blades stacked therein, each blade having a cutting edge, spaced apart elements projecting from one face of said blade lengthwise thereof to rigidify said blade against longitudinal flexing and serving to hold the blades spaced apart, said elements being parallel to each other and substantially perpendicular to said cutting edge and defining a channel therebetween, and being substantially rigid against longitudinal flexing, and said elements projecting from said blade for a distance greater than blade thickness and serving to hold adjacent blades spaced apart for that distance whereby a razor can be entered into said channel through said mouth to engage and seat a blade at one end of the stack.

2. For use with a razor blade having a side cutting edge and with a container; a safety razor comprising a head having a handle secured thereto, said head comprising a base and a cap overlying the base and having one end free of the base and its other end integral with said base, the cap when idle having a part closer to the base than the thickness of a blade, and said cap being biased toward the base, whereby an inserted blade is clamped resiliently between the cap and base.

3. For use with a razor blade having a side cutting edge and with a container, a safety razor comprising a head having a handle secured thereto, said head comprising a base having a centering bar and safety bars on each side of the centering bar, a cap overlying the centering bar and having one end free and the other end connected to an end of the base, the cap when idle having a part closer to the base than the thickness of a blade, and said cap being biased toward the base, whereby an inserted blade is clamped resiliently between the cap and base.

4. A safety razor as set forth in claim 3, wherein the safety bars are parallel to a side cutting edge of the blade when the blade is in the razor.

5. A razor as set forth in claim 4, wherein the cap has side edges, said edges being parallel to a side cutting edge of the blade when the blade is in the razor.

6. A safety razor as set forth in claim 5, wherein said cap is integral to said base at one end thereof.

7. For use with a container having a loading zone

and an extracting zone similarly contoured at the mouth thereof, a safety razor having a head provided with a cap having a top surface, said top surface being provided with a central longitudinal rib tapering into the sides of

5 the cap so as to fit the contours of the mouths, said cap also having a base having a centering bar and safety bars on each side thereof, said cap overlying said base and having one end free of the base, the cap when idle having a part closer to the base than the thickness of the blade, said cap being biased toward the base, whereby an inserted blade is clamped resiliently between the cap and the base.

8. A safety razor as set forth in claim 7 wherein the end of the rib at the free end of the cap is tapered toward the base.

9. For use with a razor blade and with a safety razor, a razor blade container having a chamber adapted to contain a stack of fresh razor blades, said container including a loading zone having a mouth, means feeding said stack towards the mouth of the loading zone, means for locating the stack in the container, said locating means including at least one guide rib, said rib extending throughout the chamber for the fresh blades but terminating short of the mouth of the loading zone, and vertical control means at the mouth of the loading zone to control the lowermost fresh blade vertically, said vertical control means including lateral control means for laterally controlling said lowermost blade.

10. For use with a razor blade having blade locating means and spaced parallel elements extending downwardly therefrom and with a safety razor, a razor blade container having a chamber adapted to contain a stack of fresh razor blades, said container including a loading zone having a mouth, means feeding said blades towards the mouth of the loading zone, means for locating the blades in the container, and reaches projecting inwardly from each side of the chamber, said reaches being disposed below the blade in the loading zone and being located closer to one another than the side cutting edges of said blade, the inner edge of the reaches being spaced apart a distance slightly in excess of the distance between the elements projecting from the razor blade, whereby the reaches coact with the elements of the razor blade to control the blade laterally and also coact with said blade to control the blade vertically.

11. A razor blade container as set forth in claim 10, wherein a rib is provided on the inner surface of the wall of the chamber remote from the mouth of the loading zone, said rib serving to control the blade longitudinally and to space the lowermost blade from the wall of the chamber on which the rib is disposed.

12. For use with razor blades and a safety razor having a cap and safety bars, a razor blade container having a chamber adapted to contain a stack of fresh razor blades, said container including a loading zone having a mouth, means feeding said blades towards the mouth of the loading zone, means for locating the blades in the container, and reaches projecting inwardly from each side of the chamber, said reaches being disposed below the lowermost blade and being located closer to one another than the side cutting edges of said blade, and a guide groove on the inner surface of each side of the chamber, the grooves and reaches being so spaced from one another a distance less than the distance between a safety bar of the razor and the undersurface of the cap thereof, the grooves being adapted to receive the safety bars of the razor.

13. A container as set forth in claim 12, wherein said reaches are integral with each other to form a loading guide which is separate from said loading zone and insertable therein.

14. A container as set forth in claim 13, wherein contours are provided on said loading guide similar to said guide grooves to receive the safety bars of the razor.

15. A container as set forth in claim 14, wherein a slot

is provided in the wall of the loading zone and a projection is provided on said loading guide enterable in said slot to hold the loading guide in said loading zone.

16. A container as set forth in claim 15, wherein dimples are provided on said loading guide cooperable with the razor to insure proper location of the razor in the loading zone.

17. For use with razor blades and a safety razor, a razor blade container comprising side and end walls, said container having an extracting zone including a mouth associated therewith and a chamber adapted to contain a stack of used blades, means for locating the used blades in the container, comprising at least one vertical guide rib on the inside surface of each end wall, and the guide rib at the end remote from the mouth terminating short of the extracting zone, lateral control means on the inner surface of the side walls at the ends remote from the mouth to laterally control the blade in the extracting zone of the container, and stop means associated with the lateral control means to permit entry of a razor containing a blade and prevent the blade from being withdrawn when the razor is withdrawn.

18. For use with razor blades and a safety razor, a razor blade container comprising side and end walls, said container having an extracting zone including a mouth associated therewith and a chamber adapted to contain a stack of used blades, means for locating the used blades in the container, lateral control means for controlling a blade in said mouth, and stop means associated with the lateral control means to permit entry of a razor containing a blade and prevent the blade from being withdrawn when the razor is withdrawn, said lateral control means comprising a reach on the inside surface of each side wall projecting inwardly over the top surface of the sides of the uppermost razor blade and extending from the end thereof near the mouth over approximately half of the length of the blade, said stop means comprising a resilient portion of said reach being lower than the reach to allow a blade being inserted to pass over the resilient portion and to present a stop for the blade to prevent a blade from being extracted, and means canting the uppermost blade upwardly at the end remote from the mouth and allowing the near end thereof to be disposed below the mouth, whereby a razor can be entered above the uppermost used blade.

19. A container as set forth in claim 18, wherein the said resilient portion comprises a downwardly projecting portion terminating in an upwardly pointing finger.

20. For use with razor blades and a safety razor comprising a head including a base having a centering bar and safety bars on each side of the centering bar, and a cap overlying said base, a razor blade container comprising side and end walls, said container having an extracting zone including a mouth associated therewith and a chamber adapted to contain a stack of used blades, means for locating the used blades in said stack, lateral control means for controlling the blade in said mouth, and stop means associated with the lateral control means to permit entry of a razor containing a blade and prevent the blade from being withdrawn when the razor is withdrawn, said guide means comprising a reach on the inside surface of the sides of the uppermost razor blade and extending from the end thereof near the mouth over approximately half of the length of the blade, said stop means comprising a resilient portion of said reach being lower than the reach to allow a blade being inserted to pass over the resilient portion and to present a stop for the blade to prevent the blade from being extracted, and means canting the uppermost blade upwardly at the end remote from the mouth and allowing the near end thereof to be disposed below the mouth whereby a razor can be entered above the uppermost used blade, a remote stop for the remote end of the uppermost blades, a guide groove disposed on the inner surface of each side wall, said reaches and guide grooves being spaced from one another a distance less

than the distance between the safety bars of the razor and a razor blade disposed therein, said grooves being adapted to receive said safety bars, whereby the razor is receivable in the mouth of the extracting zone with the blade entering below the reaches, said stop means being spaced a distance from the remote stop greater than the length of the blade whereby an entered blade will pass the stop means completely, said canting means being resilient and forcing the razor blade upwardly under the reach whereby it will abut the stop means when the razor is withdrawn from the extracting.

21. A container as set forth in claim 20, wherein said reaches are integral with each other to form an extracting guide which is separate from said extracting zone and insertable therein.

22. A container as set forth in claim 21, wherein contours are provided in the extracting guide similar to said guide grooves to receive the safety bars of the razor.

23. A container as set forth in claim 22, wherein a slot is provided in the wall of the extracting zone and a projecting is provided on said extracting guide enterable in said slot to hold the extracting guide in the extracting zone.

24. For use with razor blades and a safety razor comprising a head including a cap and safety bars, a razor blade container comprising side and end walls, said container having an extracting zone including a mouth, a used blade chamber communicating with said zone and adapted, said container also having a loading zone including a mouth and a chamber adapted to contain a stack of fresh blades, means separating said chambers, lateral control means associated with the loading zone to permit entry of the razor head with the cap disposed above the blade in the loading zone and to laterally control the blade in the loading zone, guiding means at the extracting zone to permit entry of the head of the razor, stop means in the extracting zone to prevent a used blade from moving out once the blade is fully inserted into the mouth, whereby on insertion of the razor and removal of the same from the extracting zone the used blade will be left therein.

25. A container as set forth in claim 24, wherein said guiding means constituting a groove in each side wall at the loading zone and the extracting zone, said grooves being adapted to receive the safety bars of the razor.

26. A container as set forth in claim 25, wherein an extracting guide is provided in the extracting zone and a loading guide is provided in said loading, said two guides being separate and insertable into said extracting zone and loading zone respectively, said two guides having containers similar to said grooves adapted to receive the safety bars of the razor, slots being provided in the side walls of the container, projections being provided on said guides enterable into the slots to hold the guides in their respective zones.

27. The combination of a razor having a head comprising a base having a centering bar and safety bars on each side of the centering bar, a cap overlying the base, said cap when idle having a part closer to the base than the thickness of a blade and said cap being biased toward said centering bar; with a blade comprising a thin strip of metal having a cutting edge, and two spaced apart parallel elements adapted to fit the centering bar of the razor to locate the blade in the razor, said spaced apart elements being spaced inwardly from the cutting edge.

28. The combination of claim 27, wherein said two elements are connected to each other by a crosspiece, and said two elements define an angle with said crosspiece of at most ninety degrees.

29. The combination of a razor having a head comprising a base having a centering bar and safety bars on each side of the centering bar, a cap overlying the base, said cap when idle having a part closer to the base than the thickness of a blade, said cap being biased toward said base, said cap having a top surface provided with a

rib tapering into the side of the cap; with a container having a loading zone and an extracting zone having a mouth, a used blade chamber associated with the extracting zone and a fresh blade chamber associated with the loading zone, guide grooves at each zone to coat with the safety bars of the razor, the mouths of both zones having a portion to receive the rib of the razor cap.

30. The combination of a blade comprising a thin strip of metal having a cutting edge and two spaced apart parallel elements, said blade having locating means comprising recesses at its end edge; with a container having a loading zone and an extracting zone, a fresh blade chamber associated with said loading zone and a used blade chamber associated with said extracting zone, guide ribs on said container cooperable with said recesses on the blade to locate the blades within the container, said guide ribs terminating short of both zones, extracting guides and loading guides provided in both zones, said guides including reaches extending away from the side walls of the container, said reaches being a distance less than the width of the strip of metal of the blade, ribs provided in the reaches of the loading guide, said ribs being spaced from each other a distance less than the distance between the elements of the blade, said extracting guide having canting means to cant the blades, the lowermost blade in the fresh blade chamber being in the loading zone, the strip of the lowermost blade in the fresh blade chamber resting on the recesses of the loading guide and other blades in the used blade chamber being stacked on the lowermost blade, the strips of said blades being spaced from each other by the said two elements of the blade, and the topmost blade in the used blade chamber lying in the extracting zone and being canted by the canting means of the extracting guide.

31. The combination of a razor comprising a head having a handle secured thereto, said head including a base having a centering bar and safety bars on each side of the centering bar, a cap overlying the base and having one end free of the base, the cap when idle having a part closer to the base than the thickness of the blade, and said cap being biased toward the base; with a blade comprising a thin, elongated, flat strip of metal having a side cutting edge and including spaced elements projecting from one face of the strip and running parallel to said edge and adapted to fit the centering bar of the razor, said elements being spaced inwardly from the cutting edges; and a dispenser having a loading zone and an extracting zone, a chamber for fresh blades associated with said loading zone and a chamber for used blades associated with said extracting zone, lateral control means in the loading zone coating with the elements of the razor blade to guide the lowermost fresh blade for lateral control only, and guides at the mouth of each zone coating with the safety bars to permit the razor to enter each zone.

32. The combination as set forth in claim 31, wherein grooves are provided at the loading and extracting zones for guiding the razor head on insertion thereof into either

zone of the container, the grooves at the loading zone being located a distance from the lowermost fresh blade less than the distance between the cap of the razor and the safety bars, whereby said cap will be inserted above the lowermost blade so that the latter is caught between the cap and the base.

33. The combination of a razor blade having a pair of spaced elongated flanges disposed parallel to a side of the blade and to one another, said flanges projecting from the blade at substantially right angles thereto; with a safety razor including a head comprising a base having a centering bar and safety bars on each side of the centering bar, the width of said centering bar being such as to snugly slidably fit between the flanges of the razor blade, a cap overlying the base and having one end free of the base, the cap when idle having a part closer to the base than the thickness of the blade, and the cap being biased toward the base, whereby an inserted blade is clamped resiliently between the cap and the base, said cap having a top surface, said top surface being provided with a central, longitudinal rib tapering into the sides of the cap; and a container having a loading zone and an extracting zone, a chamber for fresh blades associated with said loading zone and a chamber for used blades associated with said extracting zone, reaches in the loading zone coating with the flanges of the razor blade to guide the lowermost fresh blade for lateral control, guides in the mouth of each zone coating with the safety bars to permit entry of the head of the razor in each zone, said guides comprising grooves at the loading and extracting zones, the groove at the loading zone being located a distance from the lowermost fresh blade less than the distance between the cap of the razor and the safety bars, whereby said cap will be inserted above the lowermost blade so that the latter is caught between the cap and the base and the contours of the mouths of the zones fitting that of the cap.

34. For use with a razor blade container, and with razor blades, a spring having a central portion and a leg integral therewith on each side thereof, an upwardly extending tongue at one end of the central portion, said legs including a toe at each end thereof, said toe lying in a substantially horizontal plane below the tongue whereby blades disposed on top of the spring will be canted by the tongue and those disposed below will be guided parallel to the base of the container.
